KARL OSWALD, OF IRVINGTON, NEW JERSEY, ASSIGNOR TO DAVID MORGESTERN
AND MAX BRILL, PARTNERS UNDER FIRM-NAME OF MORGESTERN & BRILL.

FASTENER FOR HAND-BAGS AND THE LIKE.

1,102,541.

Specification of Letters Patent.

Patented July 7, 1914.

Application filed June 20, 1913. Serial No. 774,759.

To all whom it may concern:

Be it known that I, KARL OSWALD, a citizen of the United States, residing at Irvington, in the county of Essex and State of New Jersey, have invented certain Improvements in Fasteners for Hand-Bags and the like, of which the following is a specification.

The objects of this invention are to provide a primary and secondary lock for a hand bag and the like; to provide such a secondary lock which will resiliently resist opening by engagement with the primary lock; to provide a primary lock adapted to this purpose; to also provide a secondary lock which will fit close to the primary lock; to provide an improved U-shaped construction of secondary lock; to provide jaws to engage on the opposite sides of the bag frame; to provide such a secondary lock which has to be opened before the primary lock, but which will lock the primary lock simultaneously with locking itself; to secure simplicity of construction and operation, and to obtain other advantages and results as may be brought out in the following description.

Referring to the accompanying drawings in which like reference numerals indicate the same parts throughout the several views, Figure 1 is an elevation of a bag frame to which my improved fastening means is applied; Fig. 2 is a view from the opposite side of the fastening means showing only a portion of said bag frame; Fig. 3 is a view similar to Fig. 2 showing the secondary locking member in open position; Fig. 4 is a plan view of the device as shown in Fig. 1, showing only a portion of the bag frame; Fig. 5 is a sectional view on line A—A of Fig. 2, looking in the direction of the arrows, and Fig. 6 is a similar sectional view looking in the other or opposite direction from that indicated by the arrows and showing the secondary locking member in a partially depressed position.

In the specific embodiment of the invention illustrated in said drawings, the reference numerals 1, 2 indicate the frame sections of a hand bag or the like, said frame sections being hinged at their ends as at 3, 3 and constituting the usual frame for a hand bag.

The present invention contemplates novel means for preventing inadvertent swinging

apart or opening of these frame sections, either by accident or by thieves, without attracting the attention of the party carrying the bag, and for this purpose I provide substantially at the center of the frame on its top, a primary locking member 4, the opening of which is prevented by a resilient secondary member 5 overlying the same on opposite sides of the frame. Said primary locking member 4 preferably comprises a ring or loop 6 on one of the frame sections, as 1, extending centrally upward therefrom and providing an aperture or hole 7 facing toward the other frame section 2. This other frame section 2 carries centrally of its upper reach, opposite the loop 6, a preferably curved or inverted L-shaped post 8, riveted or otherwise secured at its lower end to the frame section 2 and curving at its other end toward the loop 6 on the first-mentioned frame section 1. A knob 9 preferably terminates the free end of said curved post 8, said knob being small enough in diameter to pass through the aperture 7 of the loop 6. When the frame sections are swung toward each other on their pivots, the centers of the knob 9 and the hole 6 are substantially in a plane perpendicular to the line of pivoting, but as shown in the drawings, the center of the knob is closer to the top of the bag frame than the center of the hole, whereby to force the knob into said hole requires a depressive force to bend the upper reach of the frame section 1 down so the knob and hole will register. It is to be understood that this deviation from the true alinement is but slight and the frame section can be depressed as above described by pressing the two sections together, the curved surface of the knob engaging the lower part of the hole and wedgingly depressing said loop and the frame section to which it is attached, so that the frame sections can be forced together. The knob 9 is also preferably notched peripherally, as at 10, in such manner as that the lower edge of the aperture will be admitted up into the notch when the frame sections are closed together, being released therefrom by a wedging action similar to that above described for closing the bag. It is for greater convenience of opening the bag that I have provided the loop 6, for, by placing one's first finger on the upper part of the loop above the post 8 and pressing on the outer end of 110

the knob 9 with the thumb of the same hand, said knob is forced out of the aperture.

The secondary or auxiliary locking member comprises a U-shaped yoke 11 adapted to lie flatwise on the top of the bag frame with its jaws 12, 13 on opposite sides of the primary locking member to prevent their opening, and for the more convenient operation and utilization of this secondary locking member, one of the jaws, as 13, has a rearwardly projecting arm 14 pivoted at its end to the side of the frame section 2 as at 15. By this means, therefore, the yoke 11 may be swung down to receive the primary locking member between its jaws or may be swung up out of the way so the said primary locking device may be released and the bag opened. For greater strength, the connecting portion of the U between the jaws 12, 13 is preferably wider than the jaws which are comparatively thin and provided with suitable reinforcing ribs 16, 17 on their outer sides. It is furthermore preferable to provide the jaws 12, 13 with depending ears 18, 19, respectively, to overlie opposite sides of the upper reach of the bag when said secondary fastening means is closed down. As shown, these ears 16, 17 are concave on their inner walls, and so proportioned and arranged that as the yoke is swung from open to closed position one of said ears, as 18, engages the protruding extremity of the knob 9 and, by virtue of the resiliency of the parts, may be depressed to closed position, snapping over said knob and underlying the outer end portion thereof. In order to open the secondary member, the same must be forced resiliently past said knob again before the said knob can be forced out of the loop. Obviously this provides increased security for the valuables contained in the bag and does so without detracting from the appearance of the bag.

When so desired a protuberance 20 may be provided on the frame section 2 over which the other ear 19 may snap, thus procuring even greater and more evenly disposed resistance to the upward swing of the yoke prerequisite for gaining entrance to the bag.

For the further convenience of the user of the bag, it is preferable to proportion and arrange the parts so that when the channel frames are swung together until the knob 9 first engages the loop 6, the ear 18, which engages the knob when closed, overreaches the top of the loop 6. Then by depressing the yoke, said ear wedgingly forces said loop toward and upon the knob which ultimately snaps into said loop and the yoke snaps down to closed position. By this means, it will be obvious that the bag need be only swung shut as far as the meeting of the knob with the loop will allow, see Fig. 6 showing the same in this

position, and both locking members snapped shut by simply depressing the secondary locking member, whereas to open the bag each locking member must be opened separately. Obviously I thus obtain the convenience of a single lock when closing the bag, and the security of the double lock for preventing thieves from opening the bag without attracting the attention of the party carrying the same.

It will be understood that the advantages and benefits of my invention may be secured to some extent by using my improved secondary locking member in combination with suitable primary locking members of different construction than the one which I have shown and described in detail, and I therefore wish to include this.

Various other modifications may be made without departing from the spirit and scope of the invention and I do not wish to be understood as restricting myself except as required by the claims when construed in the light of the prior art.

Having thus described the invention, what I claim is:—

1. The combination with a pair of hinged frame sections, of a shoulder on one of said sections, a notched knob adapted to resiliently engage said shoulder and retain said sections together, and a secondary locking member for preventing said knob from being released, said secondary locking member being retained from opening by said knob.

2. The combination with a pair of hinged frame sections, of a shoulder on one of said sections, a notched knob adapted to resiliently engage said shoulder and retain said sections together, and a pivoted yoke preventing said knob from being released, said pivoted yoke being retained from opening by said knob.

3. The combination with a bag frame comprising hinged sections, and primary locking members therefor, of a secondary locking member consisting of a U-shaped yoke secured to the bag frame and adapted to lie with its closed end transversely across the tops of the bag frame sections at one end of the primary locking members when closed and its arms extending longitudinally of said sections on opposite sides of said primary locking members, said secondary locking member being hinged to one of the bag frame sections so as to swing upwardly away from the primary locking members with the extremities of its arms moving in a path whose radius is less than the distance from its center to the opposite side of the primary locking members.

4. The combination with a bag frame comprising hinged sections, and primary locking members therefor, of a secondary locking member consisting of a U-shaped yoke hinged to the bag frame to close down

- upon the top thereof with its arms lying on opposite sides of the said primary locking members the closed end of said yoke being reinforced, and the arms increasing in resiliency toward their ends.
5. The combination with a bag frame comprising hinged sections, and primary locking members therefor, of a secondary locking member consisting of a U-shaped yoke adapted to lie with its closed end transversely across the tops of the bag frame sections at one end of the primary locking members when closed and its arms extending longitudinally of said sections on opposite sides of said primary locking members, said secondary locking member being hinged to one of the bag frame sections so as to swing upwardly away from the primary locking members and having one of its arms adapted to engage one of the primary locking members and resiliently snap past the same.
6. The combination with a bag frame comprising hinged sections, and primary locking members therefor, of a secondary locking member consisting of a U-shaped yoke adapted to lie with its closed end transversely across the tops of the bag frame sections at one end of the primary locking members when closed and its arms extending longitudinally of said sections on opposite sides of said primary locking members, said secondary locking member being hinged to one of the bag frame sections so as to swing upwardly from the primary locking members and having one of its arms adapted to engage one of the primary locking members and resiliently snap past the same and its other arm adapted to simultaneously resiliently engage the opposite side of the bag frame.
7. The combination with a bag frame comprising hinged sections, and primary locking members which when they are closed provide a lateral rounded projection toward one side of the bag frame, of a secondary locking member hinged to the bag frame to close flatwise upon the top of the bag frame and being centrally open to allow the primary locking members to project upward through said secondary locking member, one side portion of the secondary locking member adapted to resiliently snap past the said lateral projection of the primary locking members and the other side portion of said secondary locking member adapted to at the same time resiliently engage the opposite side of the bag frame.
8. The combination with a pair of hinged frame sections, of a knob on one of said sections, and a locking member pivoted to one of said sections and adapted when closed to overlie opposite sides of said frame sections and be resiliently retained from opening by said knob.
9. The combination with a pair of hinged frame sections, of a knob on one of said sections, and a locking member pivoted to one of said sections having opposite portions which close down upon opposite sides of said frame sections and simultaneously resiliently engage the knob-carrying section and the said knob respectively.

KARL OSWALD.
